CLAIM

The ornamental design for an economy class passenger seat as shown and described.

DESCRIPTION

FIG. 1 is a right forward isometric view of a first embodiment of an economy class passenger seat showing the claimed design thereof;

FIG. 2 is a right rear isometric view of the first embodiment of the economy class passenger seat of FIG. 1;

FIG. 3 is a forward view of the first embodiment of the economy class passenger seat of FIG. 1;

FIG. 4 is a rear view of the first embodiment of the economy class passenger seat of FIG. 1;

FIG. 5 is a right-side elevational view of the first embodiment of the economy class passenger seat of FIG. 1;

FIG. 6 is a left-side elevational view of the first embodiment of the economy class passenger seat of FIG. 1;

FIG. 7 is a top elevational view of the first embodiment of the economy class passenger seat of FIG. 1;

FIG. 8 is a bottom elevational view of the first embodiment of the economy class passenger seat of FIG. 1;

FIG. 9 is a right forward isometric view of a second embodiment of an economy class passenger seat showing the claimed design thereof;

FIG. 10 is a right rear isometric view of the second embodiment of the economy class passenger seat of FIG. 9;

FIG. 11 is a forward view of the second embodiment of the economy class passenger seat of FIG. 9;

FIG. 12 is a rear view of the second embodiment of the economy class passenger seat of FIG. 9;

FIG. 13 is a right-side elevational view of the second embodiment of the economy class passenger seat of FIG. 9;

(Continued)

FIG. 14 is a left-side elevational view of the second embodiment of the economy class passenger seat of FIG. 9; FIG. 15 is a top elevational view of the second embodiment of the economy class passenger seat of FIG. 9; and, FIG. 16 is a bottom elevational view of the second embodiment of the economy class passenger seat of FIG. 9. The broken lines in the figures illustrate portions of the economy class passenger seat that form no part of the claimed design.
